J. K. Smith,

Car-Door Bolt.

Patented Feb. 12. 1836.

John K. Smith, of Port Clinton, in Schuylkill County, Pennsylvania,
(Patented February 12, 1836.)

The Schedule referred to in the Letter Patent and making part of the same, containing a description in the words of the said John K. Smith himself of his improvement in the fastening for Drop Doors of Rail Roads.

To all to whom these present may come, Be it known that I, John K. Smith, of Port Clinton, in the County of Schuylkill, State of Pennsylvania, have invented a new and useful fastening for securing Drop Doors on Rail Roads Cars, and that the following is a full and exact description of the same. The doors are to be hung transverse to the car, and when shut, meet at the center, and over a level of the under part of the longitudinal bed pieces of the car. The hinges should curve to the corner of the doors which rests upon a bolt, say 14 inches wide which is supported by a plate of iron, bent so as to form a U shape for the bolt to play under the bed pieces. This plate (or support) is secured to the bed pieces by 3 bolts, the middle one passing through a long groove in the flat bolt which serves to regulate its motion. In order more easily to draw the bolt I make use of a stop piece of iron secured to the top part of the bed pieces which is curved to fit the bolt, and by it is secured in its place. This stop piece projects over the side of the bed pieces a suitable distance to rest a hooked lever against (which I have found to be most suitable) for drawing the bolt. A safety pin is attached to the side of the car by a chain, passes through the stop piece, a staple driven in the side of the bed pieces, and a square hole in the sliding bolt. This pin is to secure the bolt in its place. I do not claim the arrangement of the doors, or the hinges on them, but that I claim as my own invention, is the various pieces composing the fastening and their general arrangement. I do not claim that the sliding bolt can be supported by other fastening than those described above. But as I claim the mode of securing the

doors by means of a bolt secured under the bed pieces, and
sliding under the doors, any other mode of securing the
would be an invasion of my rights.
